United States Patent Office.

JOHN A. COOK, OF OWEGO, NEW YORK.

Letters Patent No. 87,760, dated March 16, 1869.

IMPROVEMENT IN BARREL-HEAD.

The Schedule referred to in these Letters Patent and making part of the same.

To all whom it may concern:

Be it known that I, JOHN A. COOK, of Owego, in the county of Tioga, and State of New York, have invented a new and improved Mode of Securing Heads in Barrels; and I do hereby declare that the following is a full and exact description thereof, reference being had to the accompanying drawings, and to the letters of reference marked thereon, in which—

Figure 1 is a perspective view of a barrel with the head in it, and partially locked.

Figure 2 is a sectional view of the head.

Figure 3 is a top view of the head as locked.

Figure 4 is a perspective view of the middle and bottom sections, and locking-bar, showing the manner in which they are connected.

My invention consists in a barrel-head, so constructed that it can be locked or secured in a barrel without the use of nails, or the displacement and readjustment of the hoops, as is now required.

To do this, I make my barrel-head in three sections, as shown in the drawings. The longest, or straight sides of these sections are recessed, so that they overlap each other when put together. To the bottom of the middle section is secured a cross-bar, upon the ends of which the side sections rest, and on its top is pivoted, by a centre-screw, or bolt, a cross or locking-bar, with bevelled ends.

On top of and around the outer sides of the side sections, are secured arc-shaped strips of wood, bevelled on their inside, to the same degree as the ends of the locking-bar.

The head is secured in the barrel by slipping the

ends of the centre section into the annular groove in the inside of the end of the barrel.

The side sections are then laid upon the ends of the bottom cross-bar, and the lock-bar is turned around, across all three of the sections, its bevelled ends fitting into the bevels of the arc-shaped strips of wood, thereby pressing the side sections from the centre section into the annular groove before named, by means of which the head is firmly locked in the barrel.

In the accompanying drawings—

A is the centre section, with its sides recessed, as at *a a*, fig. 4.

B is the cross-bar, attached to its bottom.

C is the locking-bar, working on the pivot C'.

D D are the side sections, and

E E are the arc-shaped strips of wood attached thereto.

The arc-shaped strips of wood E E need extend but a short way along the sides of the side sections D D, if preferred.

What I claim as my invention, and desire to secure by Letters Patent, is—

A barrel-head, constructed, arranged, and operating as herein described, consisting of the parts A and D, circular flanges E, locking-bar C, and cross-bar B, as shown.

In testimony that I claim the foregoing invention, I have hereunto set my hand, this 24th day of September, 1868.
